The ornamental design for nose pad for eyewear, as shown and described.

DESCRIPTION

FIG. 1 is a front, elevational view of a nose pad for eyewear showing my new design;

FIG. 2 is a bottom plan view thereof;

FIG. 3 is a top plan view thereof;

FIG. 4 is a right side elevational view thereof;

FIG. 5 is a left side elevational view thereof;

FIG. 6 is a perspective view thereof;

FIG. 7 is a perspective viewed from the opposite side as shown in FIG. 6; and,

FIG. 8 is a rear elevational view thereof.

The dashed lines appearing in the Figures are for environmental purposes only and as such form no part of the claimed design.
